UNITED STATES PATENT OFFICE.

CLEMENT A. S. HERCHELRODE, OF NEW YORK, N. Y.

DESIGN FOR A MATCH-BOX AND ASH-RECEIVER.

SPECIFICATION forming part of Design No. 33,914, dated January 15, 1901.

Application filed December 20, 1900. Serial No. 40,595. Term of patent 7 years.

To all whom it may concern:

Be it known that I, CLEMENT A. S. HERCHELRODE, a citizen of the United States, residing at New York, in the county of New York and State of New York, have invented and produced a new and original Design for Match-Boxes and Ash-Receiver, of which the following is a specification, reference being had to the accompanying sheet of drawings, forming part thereof.

Figure 1 is a side view of a combined match-box and ash-receiver, showing my design; and Fig. 2 is a plan view thereof.

As shown in the drawings, the leading or material features of my design consist of the chambered body A, rising from a base B, which latter is provided with a series of sur-

face depressions or concavities $b b b b$, surrounding the body A, said body A being of approximately oval cross-section, with the bases of the oval flattened and provided with curved and flat surface-panels $a a a^2 a^3$, as indicated in full lines in Fig. 1 and by dotted lines in Fig. 2.

Having described my invention, I claim—

The design for a match-box and ash-receiver, as herein shown and described.

In testimony whereof I have signed my name to this specification in the presence of the two subscribing witnesses.

CLEMENT A. S. HERCHELRODE.
